UNITED STATES PATENT OFFICE.

CLYDE UNRUH, OF PAWNEE ROCK, KANSAS.

THIMBLE.

1,231,972.

Specification of Letters Patent.

Patented July 3, 1917.

Application filed October 2, 1916. Serial No. 123,404.

To all whom it may concern:

Be it known that I, CLYDE UNRUH, a citizen of the United States, residing at Pawnee Rock, in the county of Barton and State of 5 Kansas, have invented certain new and useful Improvements in Thimbles, of which the following is a specification.

This invention relates to sewing implements, and particularly to thimbles.

10 The primary object of the invention is to provide a sewing thimble which is equipped with thread cutting apparatus so that sewing threads may be easily and quickly severed when desired. A further object is to 15 provide a cutting apparatus so arranged upon a thimble as to be capable of being actuated to cutting position by operation of the finger within the thimble. A still further object of the invention is to provide a 20 device of this character which has its cutting edge normally housed within the thimble, so as not to interfere with the fingers of the user, and also to prevent cutting of the thread or goods accidentally. 25 Still further objects reside in the arrangement of a thimble for this purpose which is of simple and inexpensive construction, which is constructed of but few simple and readily assembled parts, all so constructed 30 and arranged as to prevent wear, breakage or derangement of the same, which is easy and positive in operation, and which will prove thoroughly practical in use.

With these objects in view, together with 35 others which will appear as the description proceeds, the invention resides in the novel formation, combination and arrangement of parts, all as will be described more fully hereinafter, illustrated in the drawings, and 40 particularly pointed out in the claims.

In the drawings:—

Figure 1 is a side elevation of a thimble constructed in accordance with the invention;

45 Fig. 2 is a longitudinal sectional view taken through the thimble, and showing the cutting mechanism in inoperative position; and

50 Fig. 3 is a view similar to Fig. 2, and illustrating the cutting mechanism moved to operative position.

Referring now more particularly to the drawing, 4 indicates the body portion of a conventional form of sewing thimble, which

is provided near its closed end with a laterally projecting housing portion 5. This housing portion may be formed upon the thimble at the time the latter is manufactured, or may be applied thereto very easily afterward. The housing portion is of substantially narrow width, and communicates at one end with the interior of the thimble, and at its other end with the atmosphere.

Pivoted upon a suitable pin 6 within the housing 5 and adjacent one end thereof is a cutting member or blade 7. This blade is of a length to fit snugly within the housing so as not to project beyond the open outer end of the same, but is capable of swinging beyond the said outer end of the housing when 65 it is desired to use the same. A spring 8 engages over a suitable stop or shoulder upon the blade, and operates to yieldably maintain the knife in retracted or inoperative position.

Secured to the rearmost edge of the cutting blade 7 in any approved manner is one end of a stem as shown, the said stem projecting beyond the inner end of the housing and into the interior of the body portion 4 of the thimble. The rearmost end of the stem is provided with a head or button 10, which is to be engaged and depressed by the finger within the thimble when it is desired that the cutting blade be moved to operative 70 75 80 85 position.

Normally, the cutting blade 7 is held retracted by the spring 8. Should the user desire to use the cutting device, the button 10 which projects slightly into the interior of 90 the thimble 4, is depressed, whereupon the blade 7 is projected beyond the outer edges of the housing 5 to cutting position. After being used, the button 10 is released and the cutting element moved to inoperative position. It is thus seen that an extremely simple cutting device for thimbles is provided. The thumb of the hand to which the thimble is applied may be pressed against the body portion of the thimble while the finger 100 within the latter is crooked or moved to operate the push button.

While the present disclosure is that of the preferred embodiment of the invention, it is obvious that various changes in the minor details of construction and arrangement of parts may be resorted to, if desired, without departing from the spirit of the invention or

exceeding the scope of the claims, and the right to make such variation in construction is hereby reserved.

What is claimed is:—

- 5 1. In a thimble, a cutting blade arranged upon said thimble and adapted to be operated from the interior of the thimble to be projected beyond the edge thereof, and means for holding said blade retracted.
- 10 2. In a thimble, a cutting element carried by said thimble and adapted to be projected beyond the edge thereof, means for holding said blade retracted, and a push button secured to said blade and projecting within said thimble.
- 15 3. In a thimble, a housing communicating with the interior of said thimble, a blade arranged in said housing and adapted to be projected beyond the outer edge thereof, a

push button connected to said blade and extending within said thimble, and means for retracting said blade and push button.

- 20 4. In a thimble, a housing formed upon said thimble and communicating at one end with the interior of said thimble, a blade pivoted within said housing and adapted to have its cutting edge projected beyond the outer edge of said housing, a spring in said housing for holding said blade within the said housing, and a push button connected to the rear edge of said blade and projecting into the interior of said thimble.

In testimony whereof I affix my signature in presence of two witnesses.

CLYDE UNRUH.
